(57) **CLAIM**

The ornamental design for a distillation unit with magnetic spinner, as shown and described.

DESCRIPTION

FIG. 1 shows a top and side perspective view of a distillation unit with magnetic spinner.

FIG. 2 shows a reverse bottom and side perspective view thereof.

FIG. 3 shows a first elevation view thereof.

FIG. 4 shows a second elevation view thereof.

FIG. 5 shows a third elevation view thereof.

FIG. 6 shows a fourth elevation view thereof.

FIG. 7 shows a top plan view thereof; and,

FIG. 8 shows a bottom plan view thereof.
